US00D745514S

(12) **United States Design Patent**
Jung et al.

(10) **Patent No.:** US D745,514 S
(45) **Date of Patent:** ** Dec. 15, 2015

(54) **ELECTRONIC DEVICE**

- (71) Applicant: **Samsung Electronics Co., Ltd.**, Suwon-si (KR)
- (72) Inventors: **Ha-Youl Jung**, San Francisco, CA (US); **Howard Nuk**, San Francisco, CA (US); **Jeff Jones**, San Francisco, CA (US); **Won-Seok Choi**, San Francisco, CA (US); **Alex Millie**, San Francisco, CA (US); **Jae-Woong Choi**, Seoul (KR)
- (73) Assignee: **Samsung Electronics Co., Ltd.**, Suwon-si (KR)
- (**) Term: **14 Years**

(21) Appl. No.: **29/508,691**

(22) Filed: **Nov. 10, 2014**

(57) **CLAIM**

We claim the ornamental design for an electronic device, as shown and described.

DESCRIPTION

FIG. 1 is a bottom perspective view of an electronic device showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof; and,

FIG. 7 is a bottom view thereof.

The broken lines in the figures illustrate portions of the electronic device which form no part of the claimed design.
